Primary Examiner — Sheryl Lane*Assistant Examiner* — Ieisha N Price(74) *Attorney, Agent, or Firm* — Neal, Gerber & Eisenberg LLP(57) **CLAIM**

The ornamental design for a fastener as shown and described.

DESCRIPTION

FIG. 1 is a front view of a fastener of our new design.

FIG. 2 is a right side view of the fastener of FIG. 1.

FIG. 3 is a perspective view of the fastener of FIG. 1.

FIG. 4 is a top view of the fastener of FIG. 1.

FIG. 5 is a bottom view of the fastener of FIG. 1.

FIG. 6 is an enlarged top view of the fastener of FIG. 1; and, FIG. 7 is an enlarged bottom view of the fastener of FIG. 1. The dashed broken lines in the drawings illustrate portions of the fastener and form no part of the claimed design.
